CLAIM

The ornamental design for an S-video type cable connector, as shown and described.

DESCRIPTION

FIG. 1 is a perspective view of an S-video type cable connector, showing my new design;

FIG. 2 is a side elevation view thereof, with the opposite side elevation view being a mirror image thereto;

FIG. 3 is a top plan view thereof;

FIG. 4 is a bottom plan view thereof;

FIG. 5 is a front elevation view thereof; and,

FIG. 6 is a rear elevation view thereof.

The broken line showing of the environment is for illustrative purposes only and forms no part of the claimed design.
